TARGET AREA CAP FOR DRIP CHAMBERS OR OTHER HEMODIALYSIS TUBING COMPONENTS

Harvey F. Swenson, Seattle, Wash., assignor to
Sweden Freezer Manufacturing Co.

Filed Dec. 18, 1972, Ser. No. 316,122

Term of patent 14 years

Int. Cl. D24—02

U.S. Cl. D83—1 F

FIG. 1

FIG. 2

FIG. 3

FIG. 1 is a top plan view of a target area cap for drip chambers or other hemodialysis tubing components;

FIG. 2 is a top perspective view thereof (the broken lines are shown for illustrative purposes only); and

FIG. 3 is a perspective view thereof.

I claim:

The ornamental design for a target area cap for drip chambers or other hemodialysis tubing components, as shown and described.
